UNITED STATES PATENT OFFICE.

EUGENE A. TOWLE, OF ST. PAUL, MINNESOTA.

CLOSURE FOR VESSELS.

1,093,501.

Specification of Letters Patent. Patented Apr. 14, 1914.

Application filed July 21, 1906. Serial No. 327,148.

To all whom it may concern:

Be it known that I, EUGENE A. TOWLE, a citizen of the United States, residing at St. Paul, in the county of Ramsey and State of Minnesota, have invented certain new and useful Improvements in Closures for Vessels, of which the following is a specification.

My invention relates to improvements in closures for vessels, such as bottles, cans, etc., its object being particularly to provide an improved form of closing cap containing a seal and a secondary closure whereby an air-tight seal is ordinarily secured, but which may be broken when the secondary closure is removed, to allow removal of the contents of the vessel.

To this end, my invention consists in the features of construction and combination hereinafter more particularly described and claimed.

In the accompanying drawings forming part of this specification, Figure 1 is a perspective view of a vessel-neck fitted with my improvements; Fig. 2 is a similar view shown partly in section; Fig. 3 is a perspective view, showing the secondary closure removed; Fig. 4 is a section of a bottle-neck fitted with my improvements and showing the secondary closure and part of the seal removed; and Fig. 5 is a section of a modified construction.

In the drawings, A represents a vessel-neck, which may form a part of a bottle, can or other vessel. The neck is formed in its free end with an outwardly-turned flange 2. Inclosing the end of the neck is my improved cap B. The lower edge 3 of the cap is bent and clamped under the flange 2 of the neck. As illustrated in the drawings, the cap is carried upward beyond the bottle-neck and then bent down and inward to form a rim or flange 4 opposed to the top of the neck. Adapted to be interposed between the cap and top of the neck is a disk 5, preferably of suitable resilient material, such as cork, which is clamped between the rim or flange 4 of the cap and the flanged upper end of the neck to form an air-tight seal. The cap is formed with a central opening adapted to be closed by a secondary closure or friction-top 6, which wedges into the recessed top of the cap, as shown in Fig. 2, and rests upon the flange 4. The friction-top 6 is formed with an upwardly and inwardly extending flange 7, which forms a convenient

recess to receive the end of a knife-blade 8 or other suitable tool to allow it to be pried from the cap. The friction-top is preferably of such height as to stand substantially flush with the upper edge of the cap.

In the construction shown in Fig. 5 I show a disk 9 of thin material such as taggers tin clamped in position by a resilient washer 10, interposed between the outer edge of the disk and flange 4. With this form the center of the disk will be cut out along the inner edge of the washer as shown in Fig. 5.

In use, the cap will be secured upon the end of the neck, as shown, clamping the disk between it and the top edge of the neck, to form an air-tight seal. When it is desired to gain access to the contents of the vessel, the friction-top 6 will be removed, as illustrated in Fig. 3, and the center of the disk cut out, as illustrated in Fig. 4. The contents of the vessel may then be poured in the ordinary manner.

By referring to Fig. 4, it will be seen that the inner edge of the cap flange 4 stands outside of the inner edge of the bottle-neck, so that when a section of disk is cut out close to the inner edge of the flange, the section of disk so cut out cannot drop into the bottle-neck, and can therefore be easily removed.

Different ways of securing the cap to the neck and different forms of secondary closure may be provided without departing from the idea of my invention, the scope of which is defined in the claim.

I claim:

In combination with a vessel neck, a closure comprising a cap embracing the end of the neck, said cap being doubled upon itself and bent to form an annular flange opposed to the end of the bottle neck, the inner edge of said flange terminating short of the interior opening of the bottle neck whereby to constitute a central opening larger than the opening through the neck of the bottle, a disk interposed between said flange and bottle neck, and a secondary closure for said central opening.

In testimony whereof I affix my signature in presence of two witnesses.

EUGENE A. TOWLE.
